UNITED STATES PATENT OFFICE.

GUSTAV WOLF, OF NEW YORK, N. Y.

DAMPER.

1,103,724.

Specification of Letters Patent. Patented July 14, 1914.

Application filed March 25, 1914. Serial No. 827,140.

To all whom it may concern:

Be it known that I, GUSTAV WOLF, a citizen of the United States, and a resident of the city of New York, borough of Bronx, in the county of Bronx and State of New York, have invented a new and Improved Damper, of which the following is a full, clear, and exact description.

This invention has special reference to improvements in dampers and more particularly to an improved damper adapted for special use in connection with the furnace attachment or combustion generator described and claimed in my prior Patent 15 #781,483, dated January 31, 1905.

The object of the invention is to provide for a very minute adjustment or regulation of the draft in the combustion chamber of a furnace, steam boiler, heater or stove, so as 20 to insure a proper combustion by a mingling of the oxygen of the atmospheric air with the combustible gases before the latter escape through the smoke pipe and flue, and at the same time permitting the escape of 25 non-combustible gases and preventing the same from being discharged into the rooms or building being heated and thereby avoiding the casualties and disagreeable odors which otherwise result.

Another object of the invention is to provide an improved damper which is provided with an attachment or auxiliary damper co-operating with openings therein so that when the main damper or damper plate is 30 closed in a position to close a smoke pipe or other escape passage, the auxiliary damper can be set to further regulate the degree of draft and prevent the entrance of cool air over the fire bed in a combustion chamber, 35 thereby permitting a maximum quantity of heat derivation consistent with a minimum supply of fuel used, at the same time permitting the escape of non-combustible gases such as carbon monoxid while permitting 40 the proper supply of air to support combustion.

With the above and other objects in view, the invention resides in the peculiar combination and arrangement of parts to be hereinafter more fully described, illustrated and claimed, it being also an object to provide a device which is simple in construction, durable and efficient in operation and not likely to get out of working order.

Reference is to be had to the accompanying drawings forming a part of this speci-

fication, in which similar characters of reference indicate corresponding parts in all the views, and in which—

Figure 1 is a side elevation of a heating furnace having its smoke pipe equipped with the improved damper; Fig. 2 is an enlarged sectional view taken longitudinally of the smoke pipe and vertically through the damper; Fig. 3 is a sectional view taken at right angles to Fig. 2 and showing the damper in elevation.

While the present invention is especially adapted for use with my prior device as above mentioned by reason of the novel and 70 desirable arrangement for supplying air in a heated condition directly over the products of combustion, whereby there is a complete mingling of the air with the gases to insure the burning of the combustible gases, 75 the device is adapted for other uses in a smoke or draft pipe.

In illustrating the application of the invention a conventional form of heating furnace 10 is shown, from the combustion 80 chamber of which a smoke pipe 11 extends for communication with the uptake or flue in order to discharge the smoke and non-combustible gases. This smoke pipe is shown as provided with an opening 12 at 85 one side adjacent to the furnace over which a laterally extending casing 13 is secured, said casing having a closure plate 14 which closes by gravity and is commonly used as a check to regulate the draft.

Whether or not the furnace or smoke pipe is provided with the draft regulator described in my patent, it is found that the carbon monoxid or carbonic oxid and other light gases of a combustible nature which are formed when carbon is burnt with a limited supply of oxygen or where carbon dioxid meets with an excessive carbon at a red heat, such gases escape into the furnace room and also pass into the rooms or building with the heated air and the result is the disagreeable odors from some of the gases, while carbon monoxid gas although colorless and possessing neither taste nor smell, causes death if inhaled in comparatively 103 small quantities. The present invention is designed to overcome these objections, and as illustrated the damper comprises a main damper plate 15 corresponding to the interior cross section of the smoke pipe and 110 provided with apertured extensions 16 on one side with rectangular apertures receiv-

ing an operating rod 17 having a handle 18 located exteriorly of the smoke pipe for turning the damper plate to the required angle in regulating the draft. A concavely 5 arcuate notch 19 is also provided in the peripheral edge of the damper plate at the top of the latter for the purpose of permitting or maintaining a slight draft when the damper is moved to an upright position to 10 close the smoke pipe and at the same time to permit the lighter and non-combustible dangerous gases to escape at the top of the smoke pipe while a whirling motion is created at the center of the damper, causing 15 the return of the heavier and combustible gases to the combustion chamber to be burned. In this operation of the device it is essential that some auxiliary inlet for air to the combustion chamber be provided and 20 thus the special adaptation of the damper to a furnace equipped with an attachment or combustion generator set forth in my prior patent. In addition to the notch 19 the damper plate 15 is provided with a plurality, 25 preferably a pair, of apertures 20, preferably located above and below the vertical center of the damper plate through which the damper rod 17 extends so as to lie above and below this rod and to dispose the apertures 30 in spaced relation a distance at least equal to the diameter of each. On the face of the damper plate disposed toward the check device which provides means for obtaining 35 access to the interior of the smoke pipe, is an auxiliary damper which consists of a flat plate 21 having a pair of apertures 22 corresponding in diameter to the diameters of the apertures 20 and spaced apart the same distance. This plate 21 is provided 40 with a slot 23 adjacent one corner and near its lower end, whereby the plate is slidably held on the main damper by engagement of a headed member 24 therethrough. This fastening member consists of a rivet or 45 screw secured to the main damper and passing through the slot with its head contacting with the face of the plate 21 so as to permit vertical adjustment of said plate on the plate 15. The plate 21 is further provided 50 with a vertical slot 25 near its upper end through which a screw 26 carried by the plate 15 extends, while a nut 27, preferably in the form of a wing nut, is engaged on the screw and is designed to be brought 55 into frictional engagement with the plate 21 to hold the latter in an adjusted position with relation to the plate 15 and regulate the relative positions of the openings of the two plates to control the draft of the furnace. The upper end of the plate 21 of the auxiliary damper is convexly arcuate, as 60 shown at 28, so as to conform to the interior face of the smoke pipe and operate to regulate the size of the opening provided by the 65 notch 19 between the edge wall of said notch

and the inner face of the smoke pipe. Thus it will be seen that access may be had to the interior of the smoke pipe by raising the cover or closure 14 or adjusting the auxiliary damper on the main damper by operation of the wing nut 27 and this can be done without danger of burning the hands by regulating the draft on the furnace. Also, when the damper is vertically disposed, as shown in Fig. 2 of the drawings, 70 with the openings or apertures of the auxiliary damper in alinement with the main damper the carbon monoxid and like gases will escape through the opening provided by the notch 19, these gases naturally ascending and hugging the top wall of the smoke pipe after being given off from the products of combustion in the combustion chamber, while air is supplied through the apertures to commingle with the heavier 75 and combustible gases in such a manner as to create a whirling motion tending to return such combustible gases with the air in a highly heated condition to the combustion chamber to be consumed. When the pipe 80 is vertical and the damper horizontally disposed or shifted from the position shown in Fig. 2, the light gases through a whirling motion escape through the apertures, while fresh air is supplied around the main damper, thus permitting the escape of the non-combustible gases through the smoke pipe and into the uptake or flue and preventing 85 the same from escaping with other gases into the house, furnace room or building 90 being heated, thereby eliminating the annoyances and casualties which have heretofore resulted from defective draft regulation. 95

Having thus described my invention, what I claim as new and desire to secure by Letters Patent is:— 105

1. The combination with a circular damper having a notch in its edge portion and a plurality of openings therethrough; of a plate 110 slideable on the damper and held from rotation and having a corresponding number of openings to aline at times with the first mentioned openings, one end of the plate being rounded to cooperate with the edge notch for varying the size thereof or close the same, adjustment of the plate serving to simultaneously cover or uncover the openings and notch, and means for holding the plate in an adjusted position on the 115 damper. 120

2. The combination with a smoke pipe leading from the combustion chamber of a furnace or the like and means for obtaining access thereto; of a damper pivoted in the 125 pipe and adapted to be turned from the exterior thereof, said damper having openings therethrough near its center and a notch in its upper edge substantially in alinement therewith, an auxiliary damper 130

slidably connected to the first mentioned damper in contact with one face of the same and having openings of corresponding number and size coöperating with the first mentioned openings and a convexly arcuate upper edge coöperating with the notch, and an adjusting member for frictionally holding the auxiliary damper at various positions of adjustment on the first mentioned damper 10 to regulate the sizes of the openings and notch or close the same, said damper when vertically disposed in a horizontal pipe with the openings and notch uncovered permitting the lighter gases to escape through the 15 notch while air is supplied through the openings, whereas when the damper is horizontal in a vertical pipe the light gases will escape through the openings while the fresh air is supplied through the notch in each 20 case to combine with the heavier and combustible gases to be consumed.

3. The combination with a smoke pipe leading from the combustion chamber of a heater and a damper mounted in the pipe 25 and having a notch in its upper edge, said damper being adapted to be set at different angular positions in the smoke pipe and

having openings therethrough near its central portion; of a plate having openings corresponding with the openings in the damper 30 and having vertical slots therein, means carried by the damper and engaged through the slots for slidably retaining the plate thereagainst, the upper edge of the plate coöperating with the notch, and a binding nut 35 for holding the plate in an adjusted position whereby when the damper is closed and the plate adjusted the light and non-combustible gases will escape therethrough while the heavier and combustible gases will return to 40 the combustion chamber, whereas when the damper is set at an angle the lighter gases will escape around the same while atmospheric air will, through a whirling motion with the heavier and combustible gases, cause the latter 45 to return to the combustion chamber.

In testimony whereof I have signed my name to this specification in the presence of two subscribing witnesses.

GUSTAV WOLF.
